TILE TRIM FOR A LAVATORY COUNTERTOP, OR THE LIKE

Joseph Stephen Wheeler, Jr., San Diego, Calif. (½ Huntington Tile, Inc., 9223 Bolsa Ave., Westminster, Calif. 92683)

Filed Dec. 29, 1966, Ser. No. 5,222

Term of patent 14 years

Int. Cl. D25—01; D23—02

U.S. Cl. D18—2

Fig. 1.

Fig. 2.

Fig. 3.

FIG. 1 is a perspective view of a tile trim for a lavatory countertop, or the like, showing my new design;

FIG. 2 is a top plane view thereof; and

FIG. 3 is a cross-sectional view taken on line 3—3 on FIG. 2.

I claim:

The ornamental design for a tile trim for a lavatory countertop, or the like, as shown.
